Primary Examiner — Garth Rademaker(74) *Attorney, Agent, or Firm* — Design IP(57) **CLAIM**

The ornamental design for a planter, as shown and described.

DESCRIPTION

FIG. 1 is a perspective view of a planter, showing a first embodiment of my new design;

FIG. 2 is a front elevation view thereof;

FIG. 3 is a rear elevation view thereof;

FIG. 4 is a left side elevation view thereof;

FIG. 5 right side elevation view thereof;

FIG. 6 is a top plan view thereof;

FIG. 7 is a perspective view of a planter, showing a second embodiment of my new design;

FIG. 8 is a front elevation view thereof;

FIG. 9 is a rear elevation view thereof;

FIG. 10 is a left side elevation view thereof;

FIG. 11 right side elevation view thereof;

FIG. 12 is a top plan view thereof;

FIG. 13 is a perspective view of a planter, showing a third embodiment of my new design;

FIG. 14 is a front elevation view thereof;

FIG. 15 is a rear elevation view thereof;

FIG. 16 is a left side elevation view thereof;

FIG. 17 right side elevation view thereof; and,

FIG. 18 is a top plan view thereof.

The broken lines shown in FIGS. 1-18 are included for the purpose of illustrating environmental subject matter only and form no part of the claimed design. The bottom surfaces of the planter, not shown, form no part of the claimed design.
